CLAIM

The ornamental design for a seat, as shown and described.

DESCRIPTION

FIG. 1 is a right side perspective view of a seat showing our new design in the foam of a sofa;

FIG. 2 is a front elevational view;

FIG. 3 is a left side view, the right side being a mirror image thereof;

FIG. 4 is a left rear perspective view;

FIG. 5 is a top plan view;

FIG. 6 is a right side perspective view of a seat showing our new design in the form of a love seat; and,

FIG. 7 is a left side perspective view showing our new design in the form of a chair.

The portion shown in the broken lines in the drawings forms no part of the design being claimed.
